UNITED STATES PATENT OFFICE

VINCENT J. WHITNEY, OF SAN FRANCISCO, CALIFORNIA

CASEMENT-WINDOW SUPPORT

Application filed July 22, 1926. Serial No. 124,278.

This invention relates particularly to that type of window supports wherein the sash is carried by a plate which is in turn pivotally connected to a shoe having sliding engagement with a track mounted on the window frame.

It is one object of the invention to provide a support of the character indicated so constructed as to effectually secure the sash against other than manual adjustment in any one of a plurality of angular positions relative to the plane of the window opening.

It is another object of the invention to provide a support of the character indicated that will permit the removal of the full width of the end of the sash to which it is attached and function as a closure for the opening so made.

In the drawing—

20 Figure 1 is a plan view of the support.

Figure 2 is a plan view of the same partly extended, part being broken away.

Figure 3 is a sectional view on line 3—3 of Figure 1, showing also a portion of a sash.

25 Figures 4 to 9 inclusive are detail perspective views of other embodiments of the invention, partly in section and parts broken away.

Referring now more particularly to the drawing, I show at 1 the base portion of a 30 track mountable upon the horizontal portion of a window frame in any suitable manner as by screws 2, the position of the window sill being indicated at 3 and the stool at 4.

The track 1 includes an upstanding edge 5 35 facing the stool 4, the said edge being turned inwardly into parallel relation to the base portion as shown at 6.

At 7 is shown a shoe slidably mounted on the track 1—5—6, and including a downwardly turned flange 8 engaging the base 1 and a downwardly turned flange 9 engaging the outer surface of the upturned edge 5 on the said track. Punched downwardly from the body of the shoe 7 are a pair of ears or 45 fingers 10—10, these fingers reaching under and engaging the under surface of the track edge 6 as clearly shown in Figure 3.

At 11 I show a plate pivotally connected to the shoe 7 as at 12 and adapted to lie parallel 50 with the base portion 1 of the track. This

plate 11 is secured to the lower edge of the sash 13 by means of screws inserted through holes 14 provided therefor, and has a flange 15 formed thereon to lie flush with the outer surface of the sash 13 and to closely approach the base 1 when the sash is closed.

An arm 16 is pivotally connected to the base 1 of the track and also to the plate 11 as shown. When the window sash is closed these several parts take the relative positions shown in Figures 1 and 3. An outward pressure upon the sash causes it to pivot about the arm 16 and the point 12 on shoe 7, the shoe 7 moving along the track 1—5—6 toward the arm 16 as shown in Figure 2.

While the frictional engagement between the several parts of the shoe and track provide a certain amount of support therefor, I provide a number of spaced indentations in the edge 6 of the track as indicated at 17 to function as detents for the shoe 7. The fingers 10 closely engage the edge 6 but are sufficiently resilient to slide over the detents 17 when extra force is applied to the sash in opening or closing, the fingers 10 normally lying between the detents 17 and effectually held against sliding thereby except under abnormal pressure as above set forth.

While the above described means for holding the shoe 7 in a given position on the track is highly efficient I have shown in additional figures other practical means for securing substantially the same result.

In Figure 4 the track is shown with notches or recesses 18 formed in part 6 thereof, the fingers 10 being somewhat wider than the notches and formed as shown to readily slide into and out of the notches under pressure.

In Figure 5 the shoe 7 carries a spring 19 on which is arranged a pin 20 and a thumb-piece 21, a number of holes 22 being formed in track part 5 in the path of travel of the pin. In this manner the shoe is effectually secured in position but easily released by removing the pin 20 from the hole 22 which it engages by pressure upon the part 21.

Figure 6 shows an arrangement where the spring 23 on shoe 7 simply carries a button 24 engaging recesses 25 in track part 5, dis-

engaging itself from the recess without the use of a finger release.

In Figure 7 notches 26 are formed in the edge of the track portion 6 and a spring 27 carried by the shoe 7 has a bent portion 28 formed therein adapted to ride into and out of the notches 26.

Still a different form is shown in Figure 8 where parts as 29 are punched out of the part 5 of the track and bent inwardly into substantially parallel relation with the track part 1, these parts 29 being but slightly spaced apart as shown at 30. In this embodiment the ends of the fingers 10 on shoe 7 are bent downwardly and slightly curved as shown so that when pressure is applied to the shoe 7 and it is caused to slide along the track the finger ends 31 will slide along the edges of the parts 29 and drop into the spaces therebetween, effectually holding the shoe against movement except when extra pressure is applied thereto to force the fingers out of the spaces 30.

In the embodiment of the invention shown in Figure 9 notches 32 are formed in the edge of track portion 6. A spring 33 mounted on the shoe 7 is bent as at 34 to positively engage and lock in notches 32, and is provided with a finger release 35.

It is to be understood, of course, that while I have herein shown and described certain specific embodiments of my invention, changes in form, construction and method of operation may be made within the scope of the appended claim.

I claim:

A window support including a track having a base having one side thereof disposed at an angle and having the free edge of said side extended inwardly and lying parallel to the base and having upwardly struck indentations formed therein, a shoe having a flange on one side thereof engaging the base between the sides of the latter and having a flange on its opposite side engaged over said angular side of the base and the inwardly extended free edge thereof, a tongue struck inwardly from the top of the shoe with its free end positioned under the free edge of the base to engage the indentations therein, a substantially L-shaped plate formed to be secured to a window sash and having one side pivoted to the top of the shoe and having its opposite side extending over said flange of the shoe and engageable with the base of the track, and an arm pivoted to the plate and to the track.

VINCENT J. WHITNEY.
